ELLIPSE TEMPLATE

Eugene A. Fuess, San Diego, Calif.
(439A W. Earl Drive, Scottsdale, Ariz.)
Filed Nov. 21, 1960, Ser. No. 70,720
2 Claims. (Cl. 33—1)

The present invention relates generally to drafting instruments and more particularly to an ellipse template.

The primary object of this invention is to provide an ellipse template with a logarithmically curved guide edge to fit various sizes of ellipses and having means to locate two further points in each quadrant of an ellipse when a first point is known, the guide edge then being placed to join the three resultant points to obtain the curve for one quadrant of an ellipse.

Another object of this invention is to provide an ellipse guide which is particularly suitable for drawing isometric ellipses, a scribed line being used as an isometric axis reference and a pair of slots to facilitate marking the major and minor axis radii, the reference line and slots being located with respect to a common center at distance proportional to their respective radii.

A further object of this invention is to provide an ellipse template adaptable to drawing ellipses at various specific angles where on identifiable radius is known, two other radii being easily located to define the required curve.

Still another object of this invention is to provide an ellipse template which can be used without the need for reference to any tables or scales, the guide means being incorporated into a single piece of transparent plastic material which serves as the sole instrument.

Finally, it is an object to provide an ellipse template of the aforementioned character which is simple and convenient to manufacture and use and which will give generally efficient and durable service.

With these and other objects definitely in view, this invention consists in the novel construction, combination and arrangement of elements and portions, as will be hereinafter fully described in the specification, particularly pointed out in the claims, and illustrated in the drawing which forms a material part of this disclosure, and in which:

FIGURE 1 is a plan view of the template for drawing isometric ellipses;

FIGURE 2 is a sectional view taken on the line 2—2 of FIGURE 1;

FIGURE 3 is a diagrammatic view of the template on a reduced scale, showing the method of obtaining the required radii;

FIGURE 4 is a diagrammatic view showing the method of drawing the ellipse quadrants; and

FIGURE 5 is a plan view of an ellipse template for drawing ellipses other than isometric.

Similar characters of reference indicate similar or identical elements and portions throughout the specification and throughout the views of the drawing.

The template, generally indicated at 10, is made from a flat sheet of transparent plastic material for maximum visibility and has a curved guide edge 12 of logarithmic spiral form, which is effectively a composite curve to fit the range of ellipses capable of being drawn with the template.

This particular curve of progressively increasing radius is well known as a guide for drawing various sizes of ellipses with different portions of the curve and no claim is made to the use of such a curve in itself. The mathematical equation for plotting the curve is related to the angle of rotation of the circle represented by the ellipse, the curved edge 12 being that used to draw isometric ellipses. For convenience, the template 10 has a straight base edge 14 and a vertical edge 16 to facilitate its use

2

with a T-square, drafting machine, or other such instruments.

Adjacent the intersection of the edges 14 and 16 is a center point 18 marked by a pair of crossed center lines 5 and 20 inscribed in the template, the center point being the starting reference for drawing any ellipse. Scribed across the template 10 is a linear visual reference element which may take the form of an isometric axis reference line 22, which may be in any convenient position on the template. 10 The reference line 22 is illustrated as straight, but may be curved according to the space available, the critical factors being that the point on the reference line nearest the center point 18 is spaced from the center point at a distance equal to the isometric radius of the smallest 15 ellipse which can be accurately drawn with the curved edge 12. Similarly, the point on the reference line 22 furthest from the center point 18 is spaced at a distance equal to the isometric radius of the largest ellipse which can be drawn with the template. Between these points 20 the line can take any form within reason and a slight extension may be provided on each end of the line for practical purposes.

On the side of the reference line 22 remote from the center point 18 is a major axis slot 24 having a guide edge 25 26 and on the other side of said reference line is a minor axis slot 28 having a guide edge 30. The guide edges 26 and 30 conform to the delineation of the reference line 22 and are spaced therefrom in correspondence with the ratio of the major and minor radii of an ellipse relative 30 to the isometric radius. The ratio of the isometric radius to the major and minor radii is a definite figure and the guide edges 26 and 30 can be positively located relative to the reference line. Thus by projecting a line from the center point 18 to intersect the reference line 22 and 35 guide edges 26 and 30, it will be found that the points of intersection represent the isometric radius and the major and minor radii, respectively, of a specific ellipse.

The first steps in drawing an ellipse are illustrated in FIGURE 3. The major axis 32 and minor axis 34 are 40 drawn from a center in the required location, together with the isometric axis 36 which, in isometric projection, is at an angle of 30 degrees to the major axis. The isometric radius is normally the one known factor when drawing an isometric ellipse and this radius is marked 45 off along the isometric axis 36 to provide a point A. The template 10 is then placed over the drawing with the center point 18 over the intersection of the drawn axes and is rotated until the reference line 22 passes through point A. The intersections of the isometric axis 36 with 50 guide edges 26 and 30 are then marked to provide points B and C, respectively.

With reference now to FIGURE 4 of the drawing, from the ellipse center indicated at O, an arc of radius OB is drawn across the major axis 32 to locate the major 55 radius point X, and an arc of radius OC is drawn across the minor axis 34 to locate the minor radius point Y. The template 10 is then placed over the drawing and adjusted until the curved edge 12 connects the three points XAY accurately, the line being drawn in to provide one quadrant of the ellipse. The various axes can be extended and the radii marked off for the other quadrants of the ellipse, the template being moved around to draw the remaining quadrants, as indicated in dash line in FIGURE 4.

65 Thus by knowing the isometric radius of the required ellipse, any isometric ellipse can be drawn, within the dimensional limits of the template, without the need for scaling any other measurements or referring to special tables. Portions or complete ellipses may be drawn as desired.

70 By way of illustrating the application to ellipses other

than isometric, a modified template 40 is shown in FIGURE 5, this template having a curved edge 42 of the appropriate logarithmic curve. In drawing ellipses other than isometric, the major radius is the known factor and the template 40 is provided with a reference slot 44 having a guide edge 45 for alignment with a major radius point with respect to a center coinciding with the scribed center point 46. Adjacent the reference slot 44 is a minor axis slot 48 having a guide edge 50 to locate the minor radius. Between the reference slot 44 and the slot 48 is an intermediate slot 52 having a guide edge 54, the purpose of this particular guide edge being to locate a third point between the major and minor radii, to provide the proper positioning of the curved edge 42, a minimum of three points being essential to define the curve. The third point located by the intermediate guide edge 54 should be on a radius from the common center at a convenient angle, such as 30 or 45 degrees from the major axis, so that the intermediate axis can easily be projected for accurate positioning of the point. In the construction of an isometric ellipse, this intermediate axis is represented by the isometric axis, which is always at 30 degrees to the major axis, for instance. The template 40 is used in a manner similar to that described above, the known radius being drawn and two other radii located therefrom by positioning the template and marking the points in the guide slots.

By way of illustration, the guide slots 44, 48 and 52 are shown as curved, but could be straight. Also, the intermediate slot 52 may be replaced by a scribed guide line, as in the isometric template, or, conversely, the reference line 22 of the template 10 may be a slot, either being suitable as a guide.

Some types of ellipse guides, such as the large sheets containing elliptical openings of various sizes, are limited to drawing specific sizes of ellipses. The template described herein, however, may be used to draw ellipses of any size within the limits of the particular template.

The operation of this invention will be clearly comprehended from a consideration of the foregoing description of the mechanical details thereof, taken in connection with the drawing and the above recited objects.

It will be obvious that all said objects are amply achieved by this invention.

It is understood that minor variation from the form of the invention disclosed herein may be made without departure from the spirit and scope of the invention, and that the specification and drawing are to be considered as merely illustrative rather than limiting.

I claim:

1. An ellipse drawing guide, comprising: a template 10 of transparent flat sheet material having a curved edge 12 of progressively varying radius corresponding to a composite curve of one quadrant of the ellipses in the range of ellipses to be drawn; a reference center point marked on said template; a linear visual reference line marked on said template and spaced from said center point; a pair of slots in said template; said slots having guide edges 14 spaced in relation to said reference line such that, along a line projected from said center point to intersect a given point on said reference line, the distance from the center point to the reference line represents a known radius of the ellipse to be drawn and the distances from the center point to said guide edges represent two other radii of the ellipse.

2. An isometric ellipse drawing guide, comprising: a template 20 of transparent, flat sheet material having a curved edge 22 of progressively varying radius corresponding to a composite curve of one quadrant of the range of ellipses to be drawn; a reference center point marked on said template; a reference line marked on said template and spaced from said center point; a pair of slots in said template on opposite sides of said reference line; said slots having guide edges spaced with relation to said reference line such that, along a line projected from said center point to intersect a given point on said reference line, the distance from the center point to the reference line represents the isometric radius and the distances from the center point to said guide edges represent the major and minor radii of the ellipse.
